UNITED STATES PATENT OFFICE

122,446

DESIGN FOR A PIN STEM FINDING

Eugene Morehouse, Providence, R. I., assignor
to B. A. Ballou & Co., Inc., a corporation of
Rhode Island

Application April 20, 1940, Serial No. 91,824

Term of patent 14 years

To all whom it may concern:

Be it known that I, Eugene Morehouse, a citizen of the United States of America, residing at Providence, county of Providence, State of Rhode Island, have invented a new, original, and ornamental Design for a Pin Stem Finding, of which the following is a specification, reference being had to the accompanying drawing forming a part thereof.

Fig. 1 is a side elevation of a pin stem finding showing my new design;

Fig. 2 is an opposite side elevation thereof;

Fig. 3 is an edge view of a pin stem finding; and

Fig. 4 is a perspective view, the parts shown in broken line in Figs. 1, 2, and 3 being omitted

The dominant feature of the design resides in the portion shown in full lines and more particularly relates to the base forming the bottom supporting wall of the catch.

I claim:

The ornamental design for a pin stem finding, substantially as shown and described.

EUGENE MOREHOUSE.
